UNITED STATES PATENT OFFICE

147,557

DESIGN FOR A RADAR TOY

George W. Kaplan, Malden, Mass.

Application November 9, 1945, Serial No. 123,627

Term of patent 7 years

(Cl. D34—15)

To all whom it may concern:

Be it known that I, George W. Kaplan, a citizen of the United States, residing at Malden, in the county of Middlesex and State of Massachusetts, have invented a new, original, and ornamental Design for Radar Toy, of which the following is a specification, reference being had to the accompanying drawing, forming part thereof.

In the drawing, the figure is a perspective view of a radar toy, showing my new design.

The opposite end of the radar toy presents the same appearance as the end shown, while the back is plain except for the knob partially shown in the perspective view.

I claim:

The ornamental design for a radar toy, substantially as shown and described.

GEORGE W. KAPLAN.
